(57) **CLAIM**

The ornamental design for an electric kettle, substantially as shown and described.

DESCRIPTION

FIG. 1 is an isometric perspective view of an electric kettle; FIG. 2 is a front elevation view of the electric kettle of FIG. 1;

FIG. 3 is a rear elevation view of the electric kettle of FIG. 1;

FIG. 4 is a left side elevation view of the electric kettle of FIG. 1

FIG. 5 is a right side elevation view of the electric kettle of FIG. 1

FIG. 6 is a top plan view of the electric kettle of FIG. 1; and, FIG. 7 is a bottom plan view of the electric kettle of FIG. 1. The broken lines in the figures illustrate environmental structures and portions of the design that form no part of the claimed design.

1 Claim, 7 Drawing Sheets
